UNITED STATES PATENT OFFICE

2,533,781

SELF-CLEANING DOOR MAT

Thomas Fallowfield, Jr., Vancouver,
British Columbia, Canada

Application November 9, 1945, Serial No. 627,551

1 Claim. (Cl. 15—36)

1

The present invention relates to new and useful improvements in apparatus adapted for cleaning shoe soles and designed particularly for cleaning the soles of shoes of persons entering large buildings, such as department stores, hotels, apartment buildings, theatres, office buildings, and the like where a large number of people enter the building, and the invention has for its primary object to remove and collect the dirt from the shoes before it is carried into the building and thus save labor in the way of janitor's service and also to protect the floor covering of the building and reduce wear thereof by dirt which is usually carried into the building by the shoes of a person.

An important object of the present invention is to provide a shoe sole-cleaning apparatus of this character adapted for mounting at the inside entrance of a building and embodying means for removing dirt from the soles of a person's shoes and conveying the same by suction means to a suitable collecting receptacle for future removal and disposal.

A further object of the invention is to provide an apparatus of this character of simple and practical construction, which is efficient and reliable in operation, relatively inexpensive to manufacture and otherwise well adapted for the purposes for which the same is intended.

Other objects and advantages reside in the details of construction and operation, as more fully hereinafter described and claimed, reference being had to the accompanying drawings forming part hereof, wherein like reference numerals refer to like parts throughout, and in which:

Figure 1 is a plan view of a complete group of the cleaning devices adapted for positioning at the inside entrance of a building.

Figure 2 is an enlarged plan view of the initial shoe sole cleaning device, and with parts broken away and shown in section, and

Figure 3 is a longitudinal sectional view taken substantially on a line 3—3 of Figure 2.

Referring now to the drawings in detail, and first with respect to the form of invention illustrated in Figures 2 and 3 of the drawings, the numeral 5 designates a housing for the cleaning mechanism and which is formed with an open top to provide an open compartment and adapted for recessing in the floor 6 of a building at the inside of the entrance thereof and with the upper edges of the housing flush with the surface of the floor.

A pair of rollers 7 and 8 are journaled in the sides of the housing 5 transversely thereof and adjacent the upper edge of the housing, and on which an endless flexible belt 9 is adapted to slowly travel.

2

The outer surface of the belt 9 is provided with a covering such as a carpet nap 10, bristles or the like to provide a soft surface for the conveyor of a type to facilitate the cleaning of the soles of shoes of persons stepping or walking thereon.

The upper flight of the endless belt 9 is supported between the rollers 7 and 8 by means of bed rails 11 supported on transversely extending frame members 12 and on which a plurality of substantially closely-spaced parallel rollers 13 are journaled in top recesses or grooves 11a in the surfaces of the bed rails.

The endless belt 9 is operated in any suitable manner such as by means of a belt 15 extending around a pulley 16 at one end of the roller 7 and around a pulley 17 secured to a shaft 18 and driven by a gear 19 from a pinion 20 connected to the shaft of an electric motor 21.

The housing 5 is formed with a vertical, transversely extending partition 22 adjacent the roller 7 to form a chamber 23 in one end of the housing and in which a dust and dirt collecting tank 23a is removably positioned.

A suction fan 25 is operatively connected to the motor 21 in the chamber 23 with its intake side connected to a suction pipe 24 by means of a flexible coupling 24a, the pipe extending to the lower flight of the covering 10 for the endless belt 9 to draw dirt and dust from the covering of the endless belt 9 through the suction pipe 24 for discharge into the collecting tank. A flexible coupling 24b also connects the discharge end of the fan to the tank. The tank 23a may comprise an electrical dust precipitator of conventional construction.

A rotary brush 26 is operatively mounted in the intake end of the suction pipe 24 in brushing engagement with the lower flight of the covering 10 of the endless belt to remove dirt therefrom, the brush 26 being operated from the motor by a belt 27.

The chamber 23 is provided with a removable cover 28 for closing the top of the same and opening said chamber so that the tank 23a may be removed when desired.

In Fig. 1 modified brushing units are shown within the housings 29 and 47. Rotary cylindrical brushes 35 and 45 are arranged longitudinally of, and transversely of, the housings 29 and 47, respectively.

The several units of the device are preferably mounted in the floor at the inside of the entrance to a building in the arrangement as indicated in Figure 1, or any one or combination of the units may be installed at the entrance, if desired, in

position so that persons entering the building may walk on the respective cleaning units and have the soles of their footwear cleaned before passing into the building.

In view of the foregoing description taken in conjunction with the accompanying drawings it is believed that a clear understanding of the construction, operation and advantages of the device will be quite apparent to those skilled in this art. A more detailed description is accordingly deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having thus described the invention, what I claim as new is:

A shoe cleaner comprising a housing forming an open top chamber and a closed chamber adjoining the open top compartment, an endless mat in the top of the open top compartment, rollers supporting said mat, a drive for one of the rollers including a motor in the closed chamber,

10 a suction pipe extending out of the closed chamber into the open top compartment with one end beneath said mat for drawing dirt from said mat into the closed chamber, a suction fan in said closed chamber and to which said pipe is connected, said fan being driven by said motor, and a rotary brush in said end of the suction pipe engaging said mat and driven by said motor.
